CLAIM

The ornamental design for a baseball equipment rack, as shown and described.

DESCRIPTION

FIG. 1 is a top, front, and left side perspective view of a baseball equipment rack showing my new design, the broken-line depiction of a baseball, cap, and bat being for illustrative purposes only and forming no part of the claimed design;

FIG. 2 is an enlarged front elevational view thereof;

FIG. 3 is an enlarged top plan view thereof;

FIG. 4 is an enlarged bottom plan view thereof;

FIG. 5 is an enlarged rear elevational view thereof;

FIG. 6 is an enlarged left side elevational view thereof; and

FIG. 7 is an enlarged right side elevational view thereof.

FIG.1.

FIG. 2.

FIG. 3.

FIG. 4.

FIG.5.

FIG.6.

FIG.7.
